UNITED STATES PATENT OFFICE.

PETER BEGHETTI, OF SAN FRANCISCO, CALIFORNIA.

WIRE PULLING AND TWISTING TOOL.

Application filed June 27, 1927. Serial No. 201,787.

This invention relates to wire tightening and twisting tools as used by the builders of wooden concrete forms preparatory to pouring concrete into the forms, and particularly 5 to such a tool as shown in my prior Patent #1,576,400 issued on March 9th, 1926, being in fact an improvement on the tool shown in said patent.

The objects of my improvements are to 10 provide to tool of the character described which will be easier to assemble with the wire to be tightened and twisted and which will be easier to operate than former tools.

In the drawings hereto Fig. 1 is a perspective view of my complete tool.

Fig. 2 is a front end view of the tool.

Fig. 3 is a plan view of the tool in position against the 2 x 4 brace of a wooden concrete wall form showing the manner of inserting the tie wires to tie the form sides together.

Fig. 4 is a side elevation of the tool as per Fig. 3 showing an intermediate or twisting position A and an upper and lower stretching or pulling position B—C.

Fig. 5 is a perspective view of a modified form of wire clamp.

Briefly described the tool comprises a double jaw for gripping the two ends of a U wire 30 which extend through the wooden concrete wall form on opposite sides of the usual 2 x 4 uprights, and a forwardly extending heel for fulcruming against the upright for pulling or stretching the wires by an upward 35 or downward movement of a handle extending from the shank of the jaws, also the handle being of crank or carpenter's brace form to facilitate twisting of the wire by revolving the tool.

40 In the drawings the shank is shown at 1 and formed rearwardly into a carpenter's brace or crank 2 preferably provided with revolvable sleeves at 3 and 4 so that the tool may be revolved without injuring the hands.

45 The shank is substantially flat on top and bottom and made with side edges flaring forwardly to form a wedge, and preferably with serrations or small teeth along the active portion of the edges as at 5.

50 A longitudinally extending slot 6 is provided in the wedge and through which extends a handle 7 having a grip 8 and the lower end of the handle provided with a cross arm 9 having two upwardly extending jaws 10 so arranged that they may be slid along the shank from position D to position E (see

Fig. 3) toward the wide part of the wedge and thereby clamp a wire strand against each edge of the shank, the teeth 5 assisting in preventing the wires from being pulled out. 60

At the forward end or base of the wedge shank is a forwardly and outwardly extending heel or fulcrum plate 11 projecting in practice about a couple of inches in front of the wide end of the wedge, while at the junction of the heel 11 to the wedge I provide a wing or twister lug having oppositely projecting offset ends 12 and above and below which ends I provide projecting horns 13 spaced from the wings sufficient to permit the passage of a wire along the edges of the wedge, the wings and horns being slightly bent toward one another as best shown in Fig. 2 so as to form a retaining space for each wire. 70

In use the nose of the fulcrum is placed against the 2 x 4 brace 14 of one side 15 of the building wall form and the ends 16 of the tie wires 17 are slipped between the horns 13 and wings 12 and between the edges 5 of the wedge and jaws 10, after which the jaws are moved forwardly by means of the handle 8 to the position "E" so as to grip the wires firmly against the edges of the wedge, and the wires if fairly tight may be twisted by means of the brace handle 3—4, or if not tight the tool is lifted to angle B (see Fig. 4) to fulcrum the heel against the brace 14 and forcibly stretch or pull the wires and the wires thereafter twisted. Also, after 90 twisting the wires, from time to time, the heel may be again fulcrumed against the brace either in position B or C and the wires again forcibly pulled to take out all slack. 95

Fig. 5 shows an optional handle 18 provided with jaws which slide along the shank 1 and dispenses with the slot 6 but necessitates threading one of the wires through adjacent the jaw portion F as it is not open for freely slipping the wires in laterally as 100 are both jaws of the construction shown in Fig. 1.

In Fig. 1 it should be remarked that the handle 7 fits loosely in the slot 6 so that the jaws are free to clamp both wires at the 105 same time.

It would of course be possible to omit the brace handle from the shank and simply extend the shank with a squared end as indicated at G so as to go in a regular carpenter's brace but the complete tool as shown is to be preferred as it is more adapted for the 110

crowbar use in pulling the wire as indicated in Fig. 4 at B and C.

After pulling the wires and twisting them to draw the concrete form sides tightly together, the wire ends are easily released by simply pulling the jaws back to the small part of the wedge by means of the handle grip 8, a cotter pin shown extending through the handle keeps the jaws in the right relation to the wedge shank while permitting plenty of freedom for wiggling the handle about to release the jaws or clamp the wires.

I claim:

1. A wire tightener and twister comprising a shank provided with a gripping member at one end for engaging the free ends of a wire loop, a wing or lug projecting from the end of the tool so positioned that one wire lies beneath and the other above one end of the wing, and a horn adjacent each end of the wing on the opposite sides of the wire ends.
2. A wire tightener and twister comprising a shank provided with a wedge plate at its end, a pair of jaws slidably mounted on said

wedge plate so as to each grip a wire against said plate, said jaws being arranged each with an open space adjacent the wedge plate whereby the wires may both be laterally slipped into position.

3. A wire tightener and twister comprising a shank provided with a gripping member at one end for engaging the free ends of a wire loop, and a fulcrum heel member extending outwardly and forwardly of the gripping member, and a pair of opposed devices under said heel member between which the ends of the wire are adapted to be laterally slipped.

4. A structure as specified in claim 2 in which said wedge plate is provided with teeth along its edges for gripping the wire.

5. A structure as specified in claim 2 in which said wedge plate is provided with a longitudinal slot and a handle slidably therein connected to said jaws for manipulating the same.

PETER BEGHETTI.
